C. MALITCH.

RAIL CHAIR.

APPLICATION FILED FEB. 2, 1922.

1,411,738.

Patented Apr. 4, 1922.

UNITED STATES PATENT OFFICE.

CHARLES MALITCH, OF HAMILTON, OHIO.

RAIL CHAIR.

1,411,738.

Specification of Letters Patent. Patented Apr. 4, 1922.

Application filed February 2, 1922. Serial No. 533,512.

To all whom it may concern:

Be it known that I, CHARLES MALITCH, a citizen of the United States, residing at Hamilton, in the county of Butler and State 5 of Ohio, have invented certain new and useful Improvements in Rail Chairs, of which the following is a specification.

My present invention, which relates generally to that type of rail joints of boltless 10 construction, more especially has reference to improvements on the form of rail chair disclosed in my Patent #1,390,919, dated September 13, 1921, and primarily my said present invention has for its purpose to render the construction of the stated patented rail chair more economical, in which the parts are especially designed for facilitating the practical application of the chair, and for holding the said parts in condition 15 to more effectively serve their intended purposes.

In my patented rail chair stated, three spikes are used for holding the chair down onto the wooden tie, and these are usually 20 so applied, that when fitting the chair or shoe under a rail base it is necessary to draw the several spikes, and by reason thereof it has required some time and much inconvenience, when assembling the parts that 25 constitute the chair, to their operative condition.

One of the objects of my present invention is to produce an improved arrangement of chair or shoe section, that provides for 30 conveniently, quickly and effectively placing the chair or shoe in the desired operative position without the need of drawing all of the spikes, as before mentioned, and in which means is provided for interlock- 35 ably holding the parts, that constitute the chair, in operative engagement with each other, and with the base of the rail sections that rest thereon.

Again, my present invention, in its more 40 complete make-up, embodies an improved cooperative combination of opposing shoe or chair members and steel wedges for interlocking with the web of the abutting rail sections, combined with an improved ar- 45 rangement of wooden wedges, and means for holding all of the parts against undue vibration and in a position from which they 50 are not readily displaced under the usual strain transmitted to the chair connection, 55 from passing trains.

Among other minor objects in view, that will hereinafter appear, as the detailed description of the parts is considered, my present invention consists in the improved arrangement and peculiar features of construction hereinafter explained, specifically stated in the appended claims, and illustrated in the accompanying drawing, in which:

Figure 1 is a perspective view of a preferred form of my improved rail chair.

Figure 2 is a horizontal section thereof taken substantially on the line 2—2 of Figure 3.

Figure 3 is a cross section of the same on the line 3—3 of Figure 2.

Figure 4 is a fragmentary horizontal section showing a modified form of the invention.

Figure 5 is a cross section of the modified form of chair or shoe shown in Figure 4.

In my present rail chair construction, the chair or shoe, in practice, is preferably ten inches long and when operatively applied it is adapted to sit down into a recess or seat 80 7^a, in the top of the wooden cross tie 7, and the said chair or shoe, as in my patented construction referred to, is secured upon the tie by a pair of spikes 5—5 at one side and a midway positioned single spike 5^a at the 85 opposite side of the chair, as shown.

In the preferred construction, shown in Figures 1 to 3, the chair is formed of two half sections 2—2, each of which includes an upwardly extending web 2^b, and the said webs 2^b of the opposing chair sections 2, are parallelly disposed, with their inner faces in parallel planes with respect to each other, as is best shown in Figure 2.

In my present and preferred construction 95 of rail chair a combination of wooden and steel wedge members is employed, and these are arranged as best shown in Figures 2 and 3, by reference to which it will be observed the steel wedges 3—3 are disposed in 100 reversed directions and each has one face formed with upper and lower flanges 30 that provide longitudinal grooves or seats 31 for receiving spacers or bearing blocks 32 which are of wood of uniform thickness throughout and that provide for effecting a gripping of the parts when the steel wedges 3—3 are driven home, as will hereinafter be further explained.

The inner face of each chair web 2^b is 110

formed with a longitudinal seat or recess 21 for the reception of supplemental wooden wedges 4-4, the latter being oppositely positioned, relatively to each other, (see Figure 2) to provide for the desired wedging of the coacting members 3-32-4 with each other and with the chair webs 2^b and the web 6 of the meeting ends of the rail sections 60-60.

10 In my present form of rail chair, means is provided to hold the steel wedges 3 from slipping back or working loose after they have been driven to effect the clamping action of the parts and the said means comprises friction elements in the nature of strips of tar paper 8, one of said strips being interposed between the adjacent faces of the steel wedges 3 and their coacting wooden wedges 4, as is clearly shown in Figures 2 and 3. The steel wedges 3, in my present construction of rail chair are somewhat longer than the opposing chair sections, the wooden fillers 32 and the wooden wedges 4 to facilitate the driving or removal of the 25 said wedges 3, as conditions may make necessary and when the chair body is made of two sections, as shown in Figures 1, 2 and 3, the wooden wedges 4 are held from slipping or working endwise by the flanges 20 that 30 constitute the ends of the recesses 21 in the chair webs 2^b.

As before stated, in the practical application of my patented rail chair, before mentioned, in case it is desired to disconnect 35 the chair for slipping it under rail ends to be seated thereon, end to end, the three spikes must be drawn to allow for the desired adjustment of the parts mentioned. In my present construction, by reason of the 40 chair being composed of two opposing half sections, when it is desired to take out and replace a rail, to provide for such result, it is only necessary to draw the single spike at one side and then pull the chair section, 45 at that side, laterally from the rail and from the opposing chair section.

The free ends of the base portion 22 of the chair sections have their co-engaging edges formed with interlocking elements engaging each other when they are adjusted in position to serve as a chair for receiving the adjacent rail ends thereof, and for such purpose the outer base edge of one section is cut down to form a somewhat resilient 50 tongue 23 that may, and preferably does, extend the full length of the said base edge and at intervals such tongue 23 is provided with upwardly projected locking lugs 24, that have outer bevelled faces 24^a to facilitate 55 slipping under a like resilient portion 26 on the base edge of the opposing chair section, the said portion 26, at suitable intervals, having locking slots 27 into which the locking lugs 24 of the tongue 23 on the 60 opposing chair section enter as the two half

sections of the chair are closed together, it being understood that in my present construction of rail chair, after the chair and rail ends are connected as described, the chair is held secured on the tie by driving 70 the spikes 5-5 and 5^a, as in my patented construction before referred to.

In the present construction, to further secure the parts from rattling and against any tendency to pull apart or separate from the 75 desired interlocked condition the webs 2^b, the steel and the wooden wedges 3 and 4, the wooden spacers 32 and the intervening paper strips 8 are each formed with elongated horizontal apertures 28, 38, 40, 45 and 80 46, adapted for being brought into register with each other and with circular apertures 61 in the webs of the adjacent rail ends, into which apertures are swaged pins 62 whose opposite ends pass through the aforesaid registering elongated slots in the wedge members, the paper strip and the webs 2^b of the chair sections, as clearly shown in Figures 2 and 3 of the drawing, from which it also will be noticed that provision is made for 90 the expansion and contraction of the rail ends, as the pins 62 tend at all times to hold the chair and the rail ends in rigid relation relatively to the up and down sagging 95 of the rail during the passage of the heavy trains thereover.

When the chair is a solid body, as in my modified form, indicated in Figures 4 and 5 of the drawings, to disconnect the chair from the rails, it is necessary to draw the 100 three spikes. In the said modified form, the chair webs 2^b are constructed without the longitudinal seats 21, that is, with flat faces against which the wooden wedges seat, and the latter are held in a tight engagement 105 with the said inner faces of the webs 2^b when the steel wedges 3 are driven home by vertical ribs 25, V shaped in cross section. The relation of the steel wedges 3, the wooden wedges 4, the tar paper strips 8 and the 110 wooden spacers 32 are cooperatively assembled the same as in the preferred construction shown and described.

From the foregoing description, taken in connection with the drawings, the complete 115 construction, the manner in which the chair parts are assembled for use or disconnected when necessary will be readily apparent to those familiar with the construction and use of rail chairs of the type to which my present invention relates and a further detailed description thereof is therefore deemed unnecessary.

What I claim is:

1. A rail joint, comprising in combination, 125 a chair including a base adapted for being spiked onto a tie, the said base having a seat, a pair of opposing rail ends whose base portions are received on the chair seat, the said chair having opposing vertically extended 130

longitudinal webs that oppose the adjacent web faces of the rail ends, a wooden wedge member mounted lengthwise along the inner face of each chair web and a steel wedge 5 interposed between each wooden wedge and their adjacent faces of the rail web.

2. A rail joint, comprising in combination, a chair including a base adapted for being spiked onto a tie, the said base having a 10 seat, a pair of opposing rail ends whose base portions are received on the chair seat, the said chair having opposing vertically extended longitudinal webs that oppose the adjacent web faces of the rail ends, a wooden 15 wedge member mounted lengthwise along the inner face of each chair web, a steel wedge interposed between each wooden wedge and the adjacent faces of the rail webs, and a wooden spacer block held in that 20 face of each steel wedge next the adjacent face of the rail webs.

3. A rail joint, comprising in combination, a chair including a base adapted for being spiked onto a tie, the said base having a seat, 25 a pair of opposing rail ends whose base portions are received on the chair seat, the said chair having opposing vertically extended longitudinal webs that oppose the adjacent web faces of the rail ends, a wooden wedge 30 member mounted lengthwise along the inner face of each chair web, a steel wedge interposed between each wooden wedge and the adjacent faces of the rail webs, and a friction element interposed between each steel 35 wedge and its cooperating wooden wedge.

4. In a rail joint, a chair comprising a base having a rail base receiving seat and an upwardly extending web along each of its opposite longitudinal edges, the said chair 40 webs being disposed parallel with each other and the rail webs, each of said chair webs having a longitudinal recessed seat extending nearly the full length thereof, a wooden wedge held in each of the said chair web 45 seats, the said wedges being positioned at the opposite sides of the rail webs and in reversed direction, and steel wedges adapted for being driven into wedged engagement with the wooden wedges and their corre- 50 sponding rail web faces.

5. In a rail joint, a chair comprising a base having a rail base receiving seat and an upwardly extending web along each of its opposite longitudinal edges, the said 55 chair webs being disposed parallel with each other and the rail webs, each of said chair webs having a longitudinal recessed seat extending nearly the full length thereof, a wooden wedge held in each of the said chair 60 web seats, the said wedges being positioned at the opposite sides of the rail webs and in reversed direction, steel wedges adapted for being driven into wedged engagement with the wooden wedges and their corresponding 65 rail web faces, each steel wedge carrying a

wooden facing block of uniform thickness throughout its length for engaging with the corresponding face of the rail web.

6. In a rail joint, a chair comprising a base having a rail base receiving seat and an upwardly extending web along each of its opposite longitudinal edges, the said chair webs being disposed parallel with each other and the rail webs, each of said chair webs having a longitudinal recessed seat 70 extending nearly the full length thereof, a wooden wedge held in each of the said chair web seats, the said wedges being positioned at the opposite sides of the rail webs and in reversed direction, steel wedges adapted for 75 being driven into wedged engagement with the wooden wedges and their corresponding rail web faces, each steel wedge carrying a wooden facing block of uniform thickness throughout its length for engaging with the 80 corresponding face of the rail web, a friction element consisting of a strip of tar paper interposed between the opposing faces of the steel and wooden wedges.

7. In a rail joint, a chair whose base has 90 a rail base receiving seat and oppositely disposed upwardly projected webs whose inner faces are spaced apart and in parallelism with the webs of the rail ends that are mounted on the chair seat, wooden wedges 95 seated lengthwise on the inner face of each chair web and held from endwise displacement, a steel wedge cooperating with each wooden wedge and adapted for being driven between said wooden wedges and their corre- 100 sponding rail web faces and a friction element interposed between each pair of cooperating wooden and steel wedges.

8. In a rail joint, a chair whose base has a rail base receiving seat and oppositely disposed upwardly projected webs whose inner faces are spaced apart and in parallelism with the webs of the rail ends that are mounted on the chair seat, a wooden wedge seated lengthwise on the inner face of each 105 chair web and held from endwise displacement, a steel wedge cooperating with each wooden wedge and adapted for being driven between said wooden wedges and their corre- 110 sponding rail web faces, a friction element interposed between each pair of cooperating wooden and steel wedges, and cross pin 115 projections rigidly secured to the rail webs that pass through the several wooden and steel wedges, the wooden elements and the 120 chair webs, the said wedges and friction element and the chair webs having elongated aligning passages through which the pins project.

9. A rail joint comprising in combination; 125 a rail chair adapted for being spiked onto a cross tie, the said chair having a seat, a pair of opposing rail ends whose base portions are received on the chair seat, the said chair being composed of two longitudinal 130

half sections, each half section having an upwardly extending web, the webs of the two opposing sections being parallelly disposed with respect to each other, the opposing edges of the base portions of the two chair sections having interlocking elements that hold the sections from lateral displacement, and wedge block devices insertable in the spaces between the upwardly extending webs of the chair sections and the adjacent

faces of the rail webs for applying lateral clamping to the chair sections and the rail webs, the said interlocking elements consisting of opposing resilient tongues on the abutting edges of the base portions, one of which has locking lugs and the other slots into which the lugs project when the two sections are closed together against the rail ends. 15

CHARLES MALITCH.
